UNITED STATES PATENT OFFICE

PETER J. HEMMER, OF NEW YORK, N. Y., AND HENRY WANECK, OF NORTH BERGEN, NEW JERSEY

DESIGN FOR A TOY SOLDIER

Application filed November 22, 1929. Serial No. 33,526. Term of patent $3\frac{1}{2}$ years.

To all whom it may concern:

Be it known that we, PETER J. HEMMER and HENRY WANECK, citizens of the United States, and residents of the city of New York, county of Queens, and State of New York, and North Bergen, in the county of Hudson and State of New Jersey, have invented the new, original, and ornamental Design for Toy Soldiers, of which the following is a specification.

Reference is had to the accompanying drawing forming part thereof, wherein

We claim:—

The ornamental design for a toy soldier substantially as shown.

PETER J. HEMMER.
HENRY WANECK.
